UNITED STATES PATENT OFFICE.

JOSEPHINE W. SULLIVAN, OF NEW YORK, N. Y.

FOLDING BACK REST.

Application filed April 23, 1924. Serial No. 708,340.

My improved device is adapted for supporting the back of a user when seated upon the ground or upon a backless bench or stool, or in a bed for invalids.

The main object of my invention is to provide a device of this character which may be compactly folded for carrying when not in use, and which will afford a comfortable but strong rest when unfolded and in operative position.

The preferred embodiment of the invention includes a back section and a seat section, both of flexible material and each reinforced by rigid frame members so designed and so connected together as to facilitate folding into compact space. The seat and back sections are hinged together and are extensible in width. Backward swinging movement of the back member is limited by flexible tension devices attached to the seat member, which latter is held in place by the weight of the person seated thereon.

In the accompanying drawings:

Fig. 1 is a perspective view of my improved back rest in operative position.

Fig. 2 is a perspective view of the device folded for carrying.

Fig. 3 is a vertical section on the line 3—3 of Fig. 1, and on a somewhat larger scale.

Fig. 4 is a view in rear elevation, and

Fig. 5 is a transverse section on the line 5—5 of Fig. 4.

My improved construction includes a back section A and a seat section B, each of which has a flexible body portion and a reinforcing frame. The frame includes side members which are connected at the upper end of the back and at the front end of the seat. Each side portion of the frame includes a pair of bars 10 and 11 connected by a suitable hinge or pivotal joint 12. The transverse frame members are so designed as to permit the side frame members to be brought close together or directly superposed during the folding of the device. I do not wish to be limited to any specific type of transverse member so long as it is capable of permitting this folding or collapsible action. Merely as an example, each transverse member includes a pair of bar sections 13 and 14, each having one end pivotally connected to a side portion of the frame. The bar sections 13 and 14 may be hinged or may be detachably connected, as for instance by means of a slide 15 of such size as to snugly enclose the two overlapping ends. By mov-

ing this slide endwise beyond the terminal of one bar section, each bar section may be swung through approximately 90° to lie in superposed relationship to the side portion of the frame. If desired the bar sections 13 and 14 may be so constructed as to prevent relative endwise movement when held together by the slide 15. As shown, one of the bar sections has a lug 16 entering an aperture 17 in the other bar section.

In addition to this main frame there is a center frame member including a bar 18 similar to the bars 10, and a bar 19 similar to the bars 11. These are connected by a hinge or other pivotal connection 20. This intermediate frame member is not directly connected to the main frame but is held in proper position in respect thereto by the flexible covering; as hereinafter described.

The frame carries or is connected by a flexible covering including a sheet 22 forming the back and a sheet 21 forming the seat. These two sheets may be of a single piece of material, if desired, and they are formed with pockets to completely enclose and protect the frame members 10, 11, 18 and 19. The transverse frame members are not inside of the pockets but are in the rear of the cloth forming the back and below the cloth forming the seat, so that access may be gained to the slides and the bar sections swung around to the proper position for folding. The pockets may be formed in any suitable manner, as for instance by making each sheet of double thickness and running lines of stitching 23 to connect the two layers and thereby define the pockets. To hold the back at the proper angle in respect to the seat, I provide flexible tension members, which may be in the form of chains 24. These are connected to the upper ends of the side frames of the back and to the front ends of the side frames of the seat. If desired these tension members may be made of adjustable length to permit the tilting of the back to different angles. As shown, the chains extend through rings and terminate in hooks which may be caught into different links.

The parts occupy substantially the positions shown in Figs. 1, 3 and 4 when the device is opened up for use. To collapse the device the back may be folded down onto the seat, and the slides moved endwise to permit separation of the bar sections 13 and 14. The apparatus will then consist of merely

the three frame sections connected solely by the cloth of the back and seat, and the device may thus be rolled or folded into a compact package as shown in Fig. 2. It will be noted that the back when in operative position includes a transverse frame member which forms an adequate support across the shoulders, and also includes a substantially vertical central member which supports the person along the center line of the back. These two frame members, together, thus cooperate to support the body in the most comfortable and satisfactory manner. The transverse members prevent the side frame members from bending toward each other, and thus the chains or other flexible tension members are held with the proper spacing upon each side of the user. Although the frame members may be made of any suitable kind of stock, they are preferably made of flat steel bars which are comparatively light in weight but present surfaces which are wide enough to distribute the pressure and avoid cutting effect.

Having thus described my invention, what I claim as new and desire to secure by Letters Patent is:

1. A combined seat and back rest having a seat section and a back section, each section including a pair of side frame members and an intermediate frame member parallel thereto, each frame member of the back section being hinged to the corresponding frame member of the seat section, flexible means connecting each side member of the seat section to the corresponding side

member of the back section to limit the swinging of one section in respect to the other, a fabric covering having pockets within which said frame members are positioned, whereby the fabric limits the spacing of the members but permits the seat section and the back section to be rolled up with the two sections in superposed relationship, and a plurality of members outside of said covering and adapted to extend from one side frame member to the other to hold said side frame members in spaced relationship and to support said intermediate frame member or to lie parallel to said frame members, and permit said rolling of said covering.

2. A back rest including a back section and a seat section hinged together, said sections each including a fabric covering and a metal frame, and said metal frames each including a pair of side frame members, a central frame member, and a plurality of transverse frame members adapted to connect said side frame members and hold them in spaced relationship or to permit them to be brought into closely juxtaposed positions, said transverse frame members being unattached to said center frame member, and said fabric covering concealing and protecting said side and center frame members, but said transverse members being outside of said covering whereby they may be operated without removing the covering.

Signed at New York, in the county of New York and State of New York, this 22nd day of April, A. D. 1924.

JOSEPHINE W. SULLIVAN.
